CLAIM

The ornamental design for a display with lights, as shown and described.

DESCRIPTION

FIG. 1 is a front elevational view of a display with lights. FIG. 2 is a rear elevational view thereof.

FIG. 3 is a left side elevational view thereof, the right side elevational view being a mirror image of the left side view; and,

FIG. 4 is a top plan view of the display with lights, the bottom plan view being a mirror image of the top plan view.
